Primary Examiner — Robin V Webster(74) *Attorney, Agent, or Firm* — Michael Best & Friedrich LLP(57) **CLAIM**

I claim the ornamental design for a shower and speaker assembly, as shown and described.

DESCRIPTION

The FIGURE is a front view of a shower and speaker assembly.

The broken lines showing the environment are for illustrative purposes only and form no part of the claimed design.

1 Claim, 1 Drawing Sheet(56)
